DESIGN FOR A WALL CABINET FOR LUBRICATING EQUIPMENT

Alexander P. Fox, University City, and August Daniel Reisert, St. Louis, Mo., assignors to Lincoln Engineering Company, St. Louis, Mo., a corporation of Missouri

Application August 23, 1940, Serial No. 94,579

Term of patent 7 years

To all whom it may concern:

Be it known that we, Alexander P. Fox and August Daniel Reisert, citizens of the United States and residents of University City, St. Louis County, Missouri, and St. Louis, Missouri, respectively, have invented a new, original, and ornamental Design for Wall Cabinet for Lubricating Equipment, of which the following is a specification, reference being had to the accompanying drawing, forming part thereof, in which

Fig. 1 is a top plan view;

Fig. 2 is a front elevational view; and

Fig. 3 is a side elevational view of a wall cabinet for lubricating equipment showing our new design.

We claim:

The ornamental design for a wall cabinet for lubricating equipment, substantially as shown.

ALEXANDER P. FOX.
AUGUST DANIEL REISERT.
